UNITED STATES PATENT OFFICE.

PETER SCHWEHM, OF HANOVER, GERMANY.

CYLINDER FOR GAS-ENGINES.

No. 884,995.

Specification of Letters Patent.

Patented April 14, 1908.

Original application filed March 1, 1906, Serial No. 303,581. Divided and this application filed February 23, 1907.
Serial No. 358,786.

To all whom it may concern:

Be it known that I, PETER SCHWEHM, a citizen of Germany, residing at Hanover, Germany, have invented new and useful Improvements in Cylinders for Gas-Engines, of which the following is a specification.

This invention relates to a gas engine cylinder which is so constructed that the waste gases are expelled with the lowest possible pressure of the scavenging air, while furthermore, the cylinder will not be weakened by the openings that serve for the escape of the dead gases.

This application is a division of a co-pending application filed by me March 1, 1906, under Serial No. 303,581.

In the accompanying drawing: Figure 1 is a longitudinal section of my improved cylinder; Fig. 2 a cross section on line 2—2, Fig. 1, and Fig. 3 a longitudinal section of part of a cylinder, illustrating a modification of the invention.

The cylinder 5 of the gas engine is provided with an inlet 6 for the explosive charge, and with an annulus having a series of exhaust ports 7. These ports open into an annular exhaust chamber that surrounds the cylinder and gradually increases in width towards the exit opening 9. The exhaust ports 7 are of different curvature, the latter being so selected that the dead gases passing through the various parts are prevented from being directed against the outer wall of the exhaust chamber, but are forced to pass along the middle of such chamber. In this way any whirls or shocks of the expelled gases are prevented and a steady, uninterrupted flow of such gases towards opening 9 is insured.

The walls or partitions 10 between the per-

forations 7 are of a height greater than the thickness of the cylinder-wall, so that the perforated section of cylinder 5 is adapted to sustain the same tension as the imperforate part thereof. In other words, the partitions 10 are constructed of sufficient strength to transmit the force of the explosion from the rear end of the cylinder to the shaft of the engine without the assistance of jacket 11 that surrounds the cylinder. In this way, jacket 11 may be cast separate from cylinder 5, so that jacket and cylinder may independently expand or contract axially owing to their difference in temperature. Cylinder 5 is provided with end flanges 5^a which are engaged by the ends of jacket 11, a watertight packing 15, being interposed between flanges and jacket.

In order to cool the walls 10, an annular channel 12 may be provided, (Fig. 3). This channel receives the cooling water through a lower opening 13 and discharges it at 14 into jacket 11. In this way the partitions 10 will be thoroughly cooled and uneven expansion of the cylinder will be prevented.

I claim:

A gas engine cylinder provided with an annular exhaust chamber, a series of curved exhaust ports connecting the cylinder with the chamber, a cooling jacket surrounding the cylinder, a cooling channel adjoining the ports and a perforated partition intermediate jacket and channel, substantially as specified.

Signed by me at Hanover, Germany, this eleventh day of February, 1907.

PETER SCHWEHM.
